UNITED STATES PATENT OFFICE.

ISAAC A. SCHWARZ, OF PHILADELPHIA, PENNSYLVANIA, ASSIGNOR TO AUGUSTUS A. LAZARUS, ISAAC A. SCHWARZ, AND BENJAMIN LIPPER, OF SAME PLACE.

DESIGN FOR TRIMMING.

SPECIFICATION forming part of Design No. 21,647, dated June 21, 1892.

Application filed May 26, 1892. Serial No. 434,498. Term of patent 3½ years.

To all whom it may concern:

Be it known that I, ISAAC A. SCHWARZ, a citizen of the United States, and a resident of Philadelphia, Pennsylvania, have invented a new and original Design for Dress-Trimming, of which the following is a specification.

My design for a dress-trimming is fully shown in the accompanying drawing, which represents a face view of a piece of the trimming.

The design comprises the two tape-like bands or ribbons *a* *a*, adjacent to the outer ends of which are narrow bands *b*, and between said bands *a* is a central band *d*. Across the faces of the bands extend cords *f*, which are flared or spread apart on each side of the central band and form outer loops, some of

which project beyond the outer bands *b*, these projecting loops being contained within arch-like loops *g*. Overlying the inner portions of the bands *a* are loops *i*, those on one band being somewhat larger than those on the other.

I claim—

The design for dress-trimming, substantially as described, and as shown in the accompanying drawing.

In testimony whereof I have signed my name to this specification in the presence of two subscribing witnesses.

ISAAC A. SCHWARZ.

Witnesses:

WILLIAM D. CONNER,
HARRY SMITH.
